UNITED STATES PATENT OFFICE.

ARTHUR S. BURKE, OF SIOUX FALLS, SOUTH DAKOTA.

DESIGN FOR A SWING.

Application filed April 30, 1926. Serial No. 17,523. Term of patent 7 years.

To all whom it may concern:

Be it known that I, ARTHUR S. BURKE, a citizen of the United States, residing at Sioux Falls, in the county of Minnehaha and State of South Dakota, have invented a new, original, and ornamental Design for Swing, of which the following is a specification, reference being had to the accompanying drawings, forming part thereof.

Figure 1 is a front elevational view of a swing, showing my new design, and Figure 2 is a side elevation thereof.

I claim:

The ornamental design for a swing, as shown.

ARTHUR S. BURKE.
